UNITED STATES PATENT OFFICE.

THOMAS DE LA MARE, OF TOOKE, UTAH.

COLLAPSIBLE FORM FOR CONCRETE PIPE.

Application filed December 8, 1923. Serial No. 679,369.

To all whom it may concern:

Be it known that I, THOMAS DE LA MARE, a citizen of the United States, residing at Tooele, in the county of Tooele and State of Utah, have invented a new and useful Collapsible Form for Concrete Pipe, of which the following is a specification.

This invention relates to a collapsible form adapted to be used as a core for concrete pipe while the same is being made, and its use is of particular advantage in connection with the making of pipe to be used underground. In the practical operation of the invention, the pipe is made ¹⁰ in situ; that is, the form is set up within the trench and the concrete is poured around the same in the position in which it is to remain.

The general object of the invention is to provide a suitable form for the purpose stated which is of novel construction, which may be made in various sizes to correspond to the sizes of pipe to be formed, which may be expanded and locked in position to form the core of the pipe, and which may be easily contracted and withdrawn from the pipe after the concrete has set.

A further object of the invention is to provide, in combination with the form above referred to, means specially constructed so that it is adapted to be easily manipulated in the trench where the pipe is to be laid, thereby to effect the desired adjustment of the form.

The invention consists further in certain details of construction and combinations of elements which will be more fully explained in connection with the accompanying drawings, which illustrate the preferred form of the invention.

In the drawings:

Figure 1 is a plan view of the invention in operative position, with parts thereof broken away and shown in section.

Figure 2 is a vertical longitudinal section.

Figure 3 is a transverse section taken on the line 3—3 of Figure 1.

Figure 4 is a transverse section taken on the line 4—4 of Figure 2.

Figure 5 is a transverse section, with the

form contracted, taken on the line 5—5 of Figure 2.

Figure 6 is a detail view of the means for expanding and contracting the outer portion of the form, the latter being shown contracted.

Figure 7 is a detail perspective view of the locking means, and showing also the adjustable connections between the actuating rod and lever.

Figure 8 is a front elevation of the dam used at the outer end of the form.

The form 10, in connection with which the invention is used, is made from resilient sheet steel, approximately in the shape of a cylinder when in normal position. The inner end of this form is received within the outer end of the concrete pipe 11, previously constructed within the trench 12, while the outer end is supported in alignment with the pipe already constructed. The form 10 at its upper side terminates in downturned flanges 13, which may be reinforced by angle irons 15 secured to the undersides thereof, and which are spaced apart so as to permit the contraction of the form, and the withdrawal of the same from the pipe after the latter has set. When the form has been set in position for the concrete to be poured around the same, the space between the flanges 13 is covered by an arcuate metallic strip 16, which completes the cylinder as shown in Figure 4. Before the concrete is poured, this strip 16 is covered by a strip of canvas 17, or similar material, so as to prevent adherence of the concrete to the strip 16. After the concrete has set, the form 10 is forcibly contracted by means hereinafter described, and separated from the concrete, whereupon the same may be easily removed along with the strip 16, and the canvas strip 17 may then be easily detached from the inside of the pipe.

For the purpose of expanding and contracting the form 10, a pair of spaced upstanding bearing members 18 are secured within the bottom of the form near its inner end, and are provided at their upper ends with opposed slots 19, within which a trunnion 20 is rotatably held by pins 21 or

other suitable means. A cylindrical member 22 is rotatably supported by the trunnion 20, and a pair of oppositely inclined wobble wheels 23 are secured to or formed integral with the member 22. These wheels 23 have deep peripheral slots 25, which are adapted to receive the downturned flanges 13 and the adjacent flanges of the angle irons 15, and as will be obvious, when the member 22 is rotated, the flanges 13 and 15 will be moved outwardly to expand the form 10, as shown in Figure 4, or moved inwardly to contract the same, as shown in Figure 5.

In order that the wobble wheels 23 may be positively rotated, the member 22 is provided between the wheels with peripheral gear teeth 26 which are adapted to mesh with a rack bar 27, said rack bar being provided with a yoke 28 embracing the member 22, and holding the rack bar always in mesh therewith. Secured to the outer end of the rack bar 27 is a sleeve 29, to which an extension rod 30 is secured, as by means of a pin 31. The outer end of the extension rod 30 extends between a pair of upstanding spaced plates 32, which are rigidly secured to the bottom of the form 10 by means of angle bars 33. The plates 32 are provided near their upper ends with rows of registering perforations 34, and the rod 30 is provided with a row of transverse horizontal holes 35, so that the rod 30, along with the rack bar 27 and the wheels 23, may be locked in any desired position by passing a pin 36 through selected holes 34 and 35. Thus, the form 10 may be locked in the expanded position to which it may be adjusted.

The extension rod 30 and rack bar 27 are moved longitudinally to expand or contract the forms through the medium of an actuating lever 37, which may be pivoted at its lower end to the angle bars 33, as shown at 38, and which is adjustably connected to the outer end of the rod 30 by means of a sleeve 39 of special construction, as shown in detail in Figure 7. This sleeve is provided at one end with a pair of opposed elongated ears 40, having series of registering perforations 41, any pair of which may be connected to the lever 37 by a pin 42. The opposite end of the sleeve 39 is provided with series of vertical perforations 43, which may be selectively connected to similar vertical holes 44 in the rod 30 by means of a pin 45. The holes 44 are offset longitudinally with respect to the holes 35, so as not to interfere therewith. Thus, it will be seen that a wide range of adjustment is secured between the rod 30 and plates 32, as well as between the rod 30 and the lever 37. It is to be noted also that the inner portion of the sleeve 39 is cut away at the sides, as shown at 46, so as to uncover the holes 35.

While the oppositely inclined wheels 23 are used to expand and contract the inner

end of the form, I prefer to employ different means for expanding and contracting the outer end of the form, and this means I will now describe. The angle irons 15 are cut away for a portion of their length, and 70 guide rods 47 substituted therefor. These guide rods are secured at their inner ends to the angle irons 15, and diverge toward the outer end of the form terminating in inwardly turned ends 48, which are secured to the outer continuations 15^a of the angle irons 15, as best shown in Figure 6. The inclined portions of the guide rods 47 extend through perforations 49 in a cross head 50, which extends transversely of the extension rod 30, 80 and is secured thereto by means of a set screw 51 or the like.

The form, as it is set up for operation, is supported at its inner end in the outer end of the pipe 11 already formed, while its outer end may be supported by a foot 52, or other suitable means, so that the concrete may be poured around the form and completely surround the same. At the outer end of the form, a dam 53 is provided, which 90 will prevent the concrete from running beyond the end of the form. This dam is provided centrally with a slot 54 within which the lever 37 may be operated, and is provided with resilient wings 55, adapted to be 95 wedged between the sides of the form and the sides of the trench 12.

In the operation of the invention, the contracted form is first inserted into the end of the pipe 11, as shown in Figures 1 and 2, and the lever 37 is then rocked toward the right until the inner end of the form is expanded to the required diameter by means of the inclined wheels 23, while at the same time, the cross head 50 riding 105 inwardly along the inclined guide rods 47 serves to expand the outer end of the form. The sleeve 39 may be suitably adjusted, with respect to the extension rod 30 and the lever 37, to effect the desired expansion. When the desired point is reached, the form is locked in that position by the insertion of pin 36 through corresponding holes 34 and 35. The arcuate cap 16 is then laid across 110 the space between the flanges 13, as shown in Figure 4, and the canvas 17 is laid on so as to cover the cap 16. The dam 53 is then wedged into the position shown in Figures 1 and 2, and the form is ready for the concrete to be poured. After the concrete has 115 been poured, the form is left in this position until the initial set has taken place, when the same may be removed by contracting of the form as will be understood.

From the foregoing description it will be 120 seen that the invention is particularly adapted to be used in a small trench, and may be manipulated with the greatest facility whether the pipe be large or small, and after 125 the concrete has set, the form may be easily 130

contracted and withdrawn and set in position for pouring the next section of pipe.

While I have described in considerable detail the specific construction of the invention, it is to be understood that this is merely illustrative and that various modifications may be made in the size, proportion, and general arrangement of the various parts, and in the specific details of construction 10 without departing from the salient features of the invention as hereinafter claimed.

What is claimed is:

1. In a device of the character described, the combination of a flexible body adapted to form a core, oppositely inclined wabble wheels supported within the body, means for simultaneously rotating said wheels, and means connecting the wabble wheels with the body so as to expand the same when 15 the wheels are rotated in one direction and to contract the body when the wheels are rotated in the opposite direction.

2. In a device of the character described, the combination of a flexible form having 20 inturned spaced longitudinal flanges, a pair of oppositely inclined wabble wheels having peripheral grooves receiving said flanges, and means for rotating the wabble wheels to separate or draw in said flanges and there- 25 by expand or contract the form.

3. In a device of the character described, the combination of a sheet metal body approximately in the shape of a cylinder to form a core, a rod disposed longitudinally 30 within the body, means for moving the rod longitudinally in either direction, oppositely inclined wabble wheels operatively connected with the body and actuated by the longitudinal movement of the rod to expand 35 or contract the body, and means for locking said rod in any desired position of adjustment.

4. In a device of the character described, the combination of a contractible and expandable body adapted to form a core, a rod disposed longitudinally within the body, a lever having one end pivoted at the bottom of the body near one end and operatively connected with one end of the rod to move the 40 same longitudinally by the rocking of the lever, means for adjusting the relation between the rod and lever, and oppositely inclined wabble wheels operatively connected with the body and actuated by the longitudinal movement of the rod to expand or contract said body.

5. In a device of the character described, the combination of a core comprising a piece of sheet metal approximately in the 45 shape of a cylinder, with inturned flanges extending longitudinally adjacent its edges, a pair of wabble wheels mounted on a transverse axis inside the core and having peripheral grooves receiving the respective flanges, said wheels being oppositely in-

clined with respect to the axis, and means for rotating said wheels to contract or expand said core.

6. In a device of the character described, the combination of a body formed from a piece of sheet metal rolled into approximately cylindrical shape and having in-turned longitudinally spaced flanges at its edges, a rod supported within the body, means for moving the rod longitudinally in either direction, and oppositely inclined wabble wheels engaging said flanges and operatively connected to said rod, to be rotated by its longitudinal movement so as to move said flanges bodily toward or away 80 from each other to cause contraction or expansion of the body.

7. In a device of the character described, the combination of a flexible form having in-turned spaced longitudinal flanges, a pair 85 of oppositely inclined wabble wheels having peripheral grooves receiving said flanges, a gear secured to said wabble wheels, a rack formed with an integral yoke embracing the gear and holding said rack 90 positively in engagement therewith, and means for reciprocating said rack to rotate the wabble wheels and thereby to expand or contract the form.

8. In a device of the character described, the combination of a substantially cylindrical form of sheet metal having in-turned spaced longitudinal flanges, a pair of oppositely inclined coaxial wabble wheels having peripheral grooves receiving said 100 flanges, and reciprocatory means for rotating the wabble wheels to spread or draw in said flanges and thereby expand or contract the form.

9. In a device of the character described, the combination of a substantially cylindrical form of sheet metal having in-turned spaced longitudinal flanges, a pair of oppositely inclined coaxial wabble wheels having peripheral grooves receiving said 110 flanges, a gear located between said wabble wheels in fixed relation thereto, a rack, means for holding the rack in constant engagement with the gear, and means for reciprocating the rack.

10. In a device of the character described, the combination of a substantially cylindrical form of sheet metal having in-turned spaced longitudinal flanges, a pair of divergent guide rods secured to the respective 120 flanges near one end of the form, a longitudinally movable actuating rod disposed within the form and having a head slidable on said guide rods for expanding and contracting the form at one end, and means 125 actuated by the rod for simultaneously expanding and contracting the other end of the form.

11. In a device of the character described, the combination of a substantially cylind-

drical form of sheet metal having inturned spaced longitudinal flanges, a pair of divergent guide rods secured to the respective flanges near one end of the form, a pair of oppositely inclined wobble wheels mounted on a transverse axis beneath the flanges near the other end of the form and having peripheral grooves receiving said

flanges, and reciprocable means slidable on said guide rods to expand or contract the 10 same and operatively connected with the wheels to rotate the latter.

In testimony that I claim the foregoing as my own, I have hereto affixed my signature.

THOMAS DE LA MARE.
